UNITED STATES PATENT OFFICE

ADOLPH GRAMLICH, OF NEW YORK, N. Y.

DESIGN FOR A DOLL HEAD OR SIMILAR ARTICLE

Application filed June 5, 1929. Serial No. 31,548. Term of patent 14 years.

To all whom it may concern:

Be it known that I, ADOLPH GRAMLICH, a citizen of the United States, and a resident of the city of New York, borough of the Bronx, in the county of the Bronx and State of New York, have invented a new, original, and ornamental Design for Doll Head or Similar Article, of which the following is a specification.

Reference is had to the accompanying drawing, forming part thereof, wherein the essential of the design consists of the arrangement of the hair on top of the head together with a mark on the forehead to represent a question mark when viewed from the front or side.

Figure 1 is a front view of a doll head showing my new design, the same being shown in connection with a body indicated by dotted lines.

Figure 2 is a side view of the doll head shown in Figure 1 the same being shown in connection with a body indicated by dotted lines.

I claim:—

The ornamental design for a doll head or similar article substantially as shown and described.

Signed at 912 Brook Avenue in the county of Bronx and State of New York, this 3rd day of June A. D. 1929.

ADOLPH GRAMLICH.
